[57] ABSTRACT

A new cultivar of *Forsythia intermedia* named 'Lemon-Screen' characterized by its vigor, upright fan-shaped habit, lemon yellow flowers, high degree of sterility, its yellow shoots, and light green foliage.

2 Drawing Sheets

1

The invention relates to a new cultivar of *Forsythia intermedia* named "Lemon-Screen", which is characterized especially by its abundance of light yellow flowers, its sterility, yellow stems with chartreuse leaves in spring, and whitish blotches on otherwise normal green leaves in summer.

The new variety was derived from a periclinal chimera mutant, which itself was derived from a sectorial mutant, which was produced in turn by subjecting rooted cuttings of the parent *Forsythia intermedia* "Lynwood Gold" (a sport of *F. intermedia* "Spectabilis") to irradiation with 1,200 rad fast neutrons.

In 1968, three hundred cuttings of "Lynwood Gold" that had been potted and held in cold storage (38° F.) for six weeks and then returned to the greenhouse for two days were irradiated with 1200 rad fast neutrons. One of the plants of this group that broke dormancy formed a shoot with variegated foliage. This plant was cut back repeatedly to induce branching and eventually formed shoots that exhibited different characteristics. Each shoot was propagated by stem cuttings over 10 vegetative generations of selection and propagation. From this plant population two vegetatively selected types and three seedlings were selected. Further propagation and testing of these selections over several more years were shown to be the stable and new forsythia varieties that are the subject of this and four other co-pending plant patent applications; viz:

2

-continued

Ser. No.	Name	Type
271,666	"Pygmy-Red"	seedling

Each differs greatly from the parent "Lynwood Gold" and also from one another.

"Lemon-Screen" was selected from a series of chimeral plants because of its distinct foliage, upright growth habit, and vigor. Cuttings from this plant have been rooted in soil and asexually propagated, and its progeny have displayed homogeneous and stable characteristics.

Throughout this specification, color names beginning with a small letter signify that the name of the color as used in common speech are aptly descriptive. Color names beginning with a capital letter designate values based on the R.H.S. Colour Chart, published by The Royal Horticultural Society of London, England.

The accompanying drawings illustrate the new variety in color as grown in Knox County within the State of Tennessee.

FIG. 1 illustrates 5½ year old "Lemon-Screen" in bloom in March-April.

FIG. 2 is a close-up view of the flowers.

FIG. 3 illustrates the "Lemon-Screen" plant in leaf.

FIG. 4 is a closer view of the foliage shown in FIG.

3.

The following characteristics distinguish "Lemon-Screen" from its parent and other *Forsythia* cultivars:

THE PLANT

The "Lemon-Screen" plant form is tall and vigorous, with an upright, fan-shaped habit. "Lemon-Screen" ultimately reaches up to 10 ft. in height. The "Lemon-

Ser. No.	Name	Type
272,063	"Lemon-Screen"	vegetative selection
273,489	"Tinkle Bells"	vegetative selection
271,919	"Minikin"	seedling
271,665	"Fairy Land"	seedling

"Screen" shrub is naturally open and graceful but is easily pruned as a tall, flowering screen in spring; it is hardy in Zone 6b or lower. Because of its vigor, "Lemon-Screen" is conveniently produced in the nursery field, but small plants can be grown in containers for a year if cut back substantially. The cultivar is particularly suited for landscape purposes, especially as a tall barrier or visual screen. "Lemon-Screen" will branch out quickly when vegetative shoots are pruned back, making the plant suitable in traffic or crash barriers, where dense plantings are used.

Its parent, "Lynwood Gold", by contrast is tall and slender—a straight upright variety with erect stems and which attains a height of 6 ft. to 7½ ft. at maturity.

FLOWER

"Lemon-Screen" has light lemon yellow flowers (Yellow 6C) that are 1½ in. to 1¾ in. in diameter. The internodes are 1" to 2" long on flowering wood. Flowering is early and profuse, with four and up to eight flowers per node on some portions of some stems. The corolla lobes are somewhat reflexed. Flowers have four petals and are sometimes fasciated. The flowers have aborted stamens and/or pistils; consequently, "Lemon-Screen" possesses a high degree of sterility.

The "Lynwood Gold" parent is fertile and has pistils that extend well above its pollen sacs, is late flowering and its medium sized flowers (about 1" to 1½" in diameter) are almost evenly spaced on the stem. The flowers of "Lynwood Gold" are brilliant yellow (lighter than its parent, *F. Spectabilis*). The corolla lobes of "Lynwood Gold" are reflexed and its petals are elliptic.

SHOOTS

The mature shoots of "Lemon-Screen" are yellow and pith is slightly lamellate between nodes.

The stems of the "Lynwood Gold" parent are green when young and brown when mature; they are a bit stiff; the pith at the nodes is lamellate, and on one year shoots, the stems between nodes are hollow.

FOLIAGE

The "Lemon-Screen" leaves are simple, serrate, acuminate at the tip, and attenuate at the base. The size of the leaves is not a distinguishing characteristic. The "Lemon-Screen" leaves which appear in the spring are chartreuse or of about a Yellow-Green 151 B color. In the summer the mature leaves are in the Yellow-Green 144 A/C range and have a Yellow-White 158 A, irregular blotch with no defined edge covering about 25-30% of the leaf surface and that extends outward from the mid rib and veins and contrasts with the green colored portions of the leaf. Fall foliage is Greyed Purple 156B. The summer foliage is disease and insect resistant. The young chartreuse leaves which appear after flowering are striking and suggest the plants are in bloom again. Summer pruning leads to the appearance of shoots with leaves that are chartreuse when young.

The leaves of the "Lynwood Gold" parent, on the other hand, are ovate lanceolate in shape and about 3" to 4½" long and about 1" to 1½" wide. Both young and old leaves are deep green in color.

To facilitate the comparison of the characteristics and features of "Lemon-Screen", the subject of this application, and its parent, "Lynwood Gold" and also with the four other new mutant offspring varieties of "Lynwood Gold" referred to above, there are attached hereto as Tables 1-5 comparative tabulations of the characteris-

tics and properties of parent and its five offspring mutants that were developed from a single irradiated plant of "Lynwood Gold." Table 1 compares "Lemon-Screen" and its parent "Lynwood Gold". Table 2 compares "Lemon-Screen" and "Pygmy-Red". Table 3 compares "Lemon-Screen" and "Tinkle Bells". Table 4 compares "Lemon-Screen" and "Minikin". Table 5 compares "Lemon-Screen" and "Fairy Land".
